MECHANICAL OIL-PUMP.

1,212,682.

Specification of Letters Patent. Patented Jan. 16, 1917.

Application filed November 29, 1915. Serial No. 63,937.

To all whom it may concern:

Be it known that I, HENRY RITTER, a citizen of the United States, and a resident of the city of Cincinnati, in the county of Hamilton and State of Ohio, have invented certain new and useful Improvements in Mechanical Oil-Pumps, of which the following is a full, clear, and exact description, reference being had to the accompanying drawings, forming part of this specification.

My invention relates to mechanical oil pumps for use in oiling engines and the like, and capable of forcing oil against high pressure. In pumps of this nature, it is highly desirable to have the various parts accessible and of the highest mechanical efficiency.

It is the object of my invention to provide an oil pump in which the various pumping units are secured complete to the lid of the oil box, so that by removing the lid all of the parts of the pump are removed also.

It is also the object of my invention to locate the checks for the force pump so that they are above the lid and easily accessible, and to provide a sight feed compact with the body of each unit.

I also have as an object the adjustability of the amount of feed through the sight, and the locating of the driving means for the pump in the oil box, with the pump itself above the lid of the box, so that its checks are accessible as above stated.

These various objects and other advantages to be noted I accomplish by that certain construction and arrangement of parts to be hereinafter more specifically pointed out and claimed.

In the drawings, Figure 1 is a top plan view of the pump, showing one unit only for purposes of clearness. Fig. 2 is a left side elevation of the same. Fig. 3 is a front elevation of the same. Fig. 4 is a section taken on the line 4, 4, of Fig. 1. Fig. 5 is a section taken on the line 5, 5, of Fig. 1. Fig. 6 is a detail section on the line 6, 6, of Fig. 4, showing the force pump and its checks. Fig. 7 is a similar section of a modified construction showing disk instead of ball check valves.

The oil box has a bottom 1 and sides 2, the same being cut off at an angle at 3 on one corner for mounting an indicator gage. An opening (not shown) is formed in the base of this cut off portion, communicating with the interior of the box, and set over it is a

glass tube 5 for the indicator gage. The box has a lid 6 which is screwed down tight on the sides thereof and extends over the cut off corner. A screw 5^a set into the lid at this corner projects down into the tube 5 and holds it in place. The height of the oil in the gage will then indicate the height of the oil in the oil box.

Housings 7, 8, for journaling the driving shaft of the pumps are mounted in the sides 65 of the box in any desired manner, and the shaft 9 is mounted in these journal housings. The housing at the left extends outwardly at 8^a and the shaft protrudes at this end, the journal being packed in the custom- 70 ar manner at 10.

A bearing sleeve 11 is tightly mounted on the portion 8^a of the shaft housing and a ratchet gear 12 is loosely mounted thereon outside of the sleeve. A cross member 13 75 on the outer face of this ratchet is secured tightly to the end of the driving shaft by a nut 14. The shaft passes through the cross member and the nut screws onto the shaft and abuts against the cross member, thereby 80 holding the parts together.

Mounted on a bracket 15 secured to the side of the box is a spring stop-pawl 16 which enforces movement of the gear 12 in but one direction, and on the sleeve is 85 mounted a rocker arm 17 on which is mounted at 18 a spring pawl 19 which meshes with the gear. A handle 20 inserted into the end of this rocker is coupled up to some reciprocating part of the engine mechanism, 90 and as the rocker is moved the gear will be rotated in one direction, thereby rotating the driving shaft.

The box is shown as being quite narrow and but one pumping unit is shown, which 95 will now be described. It is desired to note that the widening of the box and the further extending of the driving shaft will permit as many separate pumping units as may be desired to be mounted over and be driven 100 by the shaft.

The mechanism will first be described for elevating the oil from the box into the chamber at the base of the sight feed, it being understood that the pump forces the oil from thence out into the desired part to be oiled.

At either side of the pump plunger opening, in the lid of the box, are cast with the lid the depending arms 21, 21. These arms have lugs 22, 22, at each side, and a casting 110

23 is provided having corresponding arms 24, 24, whose lugs are screwed to the lugs 22, thereby forming a frame or housing for an eccentric yoke or strap 25. The eccentric shaft 26 is journaled between the two sets of arms forming this housing, and on this shaft is mounted and secured by a pin 27^a the eccentric 27, which lies inside of the eccentric strap 25. A gear 28 is mounted on the extended end of the shaft 26, and this gear is arranged to mesh with a gear 29 on the driving shaft 9 of the pump. When further units are desired, they are strung along on the eccentric shaft as desired, using the single set of gears 28, 29, and the common driving shaft 9 for driving the eccentric shaft.

In the casting 23 directly between the arms 24 thereof is formed a socket 30, in which reciprocates the guiding plunger 31 secured to the base of the eccentric strap. This plunger is cored at 32 and in its base has a chamber 33 closed by a check ball 34. The socket is open at the bottom and has a check 35 in the opening. Thus when the driving shaft is turned, the eccentric will cause the strap to move up and down and the plunger 31 will pump oil up into the hollow of the eccentric strap as well as serve as a guide and holder for the said eccentric strap.

Mounted between lugs (not shown) at the one side of the strap is an interiorly screw-threaded sleeve 36. A pump rod or plunger 37 is held adjustably in said sleeve by screw-threads 38 on the rod, and this plunger has a smooth upper end 39 which extends out through the lid of the box. By means of a knurled head on the upper end, the position of the plunger with regard to the eccentric strap may be adjusted, by screwing it through the sleeve 36, and the plunger is guided at its upper end by means of the lid.

A chamber 40 is formed in the casting 23 directly beneath this plunger or pump rod 37, and the rod reciprocates in this chamber when the eccentric strap is actuated. A vertical passageway 41 in this casting communicates at its upper end with the chamber 40, at 42, and when the rod 37 is raised oil will be drawn up at 41, across at 42, and into the base of the chamber 40. No check is needed at this point because the chamber is below the inlet 42.

A passageway 43 runs from the base of the chamber into another passageway that communicates with a tube 44. The passageway 43 is closed by a check ball 43^a which is seated just below the passageway to the tube. The screw 45 closes the opening necessary to form the passageway 43, as is customary and allows access to the ball check.

When the plunger 37 is forced downwardly by the eccentric, it will force oil out

of the base of the chamber and through the passageways, into the tube 44. The check will prevent pulling back of the oil upon return of the plunger. The passageway 41 being the oil intake, is protected by a strainer 46^a, as is the usual procedure. The adjusting of the position of the plunger 37 with regard to the strap limits or extends the downward movement of the plunger in the chamber 40. Therefore when it is desired to pump out only part of the oil in the chamber, the plunger should be screwed up through the sleeve 36, and vice versa when more oil is to be pumped. To prevent the plunger 37 from turning, I provide the spring-pressed pin 37^a which engages in one of the longitudinal notches 37^b in the plunger.

It is to be noted of the parts so far described that they are located inside of the chamber, serve to elevate oil from the chamber into a tube 44, and that all of these parts are suspended from the lid of the box and are removable with the lid.

Mounted on the top of the lid is a casting forming the casing for the force pump mechanism. This casing has a base 46 which is secured to the top at one side by the stuffing box 47 which screws into the lid. The eccentric strap heretofore mentioned has connected to its upper side the pump rod 48, and this rod extends up through the stuffing box 47. The other end of the base 46 has a screwthreaded tubular extension 49 that passes through the lid, and is held in place by a nut 49^a that is screwed onto it beneath the lid.

A plug 49^b that screws into the extension 49 serves as a coupling member with the end of the tube 44, and in the upper end of this plug is seated a ball check 50. A trunk 51 extends upwardly from this opening at 49, and is adapted to be kept filled with oil by the lower pump already described. It extends upwardly and surrounds the pump mechanism and chamber to be hereinafter described, terminating at 52 in an opening into which is secured tightly the sight feed tube 53. A circular seat 54 is formed at this point in the casting for the glass tube 55 of the sight feed, and the feed tube has formed on its upper end a screwthreaded tubular extension. A cap 55^a for the sight feed glass has an aperture for a screw 56, which is screwed into the tubular extension 53^a on the sight feed tube, thereby holding the glass in place.

It will be understood that as the interior pump operates, oil will be raised up through the tube 53 and will drop out of the end thereof down through the glass tube of the sight feed. The oil falls into a chamber 57 formed in the casting beneath the seat for the glass and from thence through a passageway 58 into small chamber 59 formed in an

extension of the casting and closed by a screw plug 60. The inlet to this chamber is closed by a ball check 61, and the upper end of the chamber is closed by a ball check 62.

- 5 A passageway 63 from this chamber leads into the vertical chamber 64, within which reciprocates the pump rod 48, said chamber also serving as a guide for the rod, as its motion will not carry its end beyond the chamber. The chamber is broadened at 64^a at its base and the stuffing box 65 is provided for packing the entrance of the rod into the chamber. A passageway 66 from the top of this chamber communicates with the outlet 10 67 also formed in the casting, the same having in its end any desired union coupling 68. A ball check 70 closes the passageway 66 at the top and a screw plug 69 closes the aperture in the casting opening into the said 15 passageway.

It is obvious from the above that the force pump rod when it is moved downwardly draws oil by the checks 61 and 62 and into the pump chamber. When it is moved upwardly, it forces the oil out of the passageway 66 by the check therein and into the outlet pipe.

Instead of using ball checks 62 and 70, in many instances I prefer to employ valve 30 disks 62^a and 70^a, as shown in Fig. 7, with a spring 81 for the disk valve 70^a. With this construction, a tight seat can be readily obtained, and a very slight clearance provided for the lift of the valves.

- 35 The check 50 at the base of the trunk helps to prevent sucking back and bubbling through the sight feed tube. The two checks in the chamber 59 that lead directly to the force pump give ample protection against 40 pumping air back into the sight feed, as the force pump has a greater stroke than is necessary to handle the oil that falls under reduced conditions of feed into the sight feed reservoir.

- 45 All the pumps are vertical, and the drive of the main force pump is in direct line with the eccentric. The ball checks of this upper pump are all outside of the oil reservoir and immediately accessible, and the various 50 features of advantage in mounting of parts as stated in the introductory matter, fully accomplished.

Various modifications of structure will, of course, be possible without departing from 55 the spirit of my invention, and it is not desired that the claims be limited to precise structure where the same is not definitely called for.

Having thus described my invention, what 60 I claim as new and desire to secure by Letters Patent, is:—

1. In a force feed lubricator, an oil reservoir, a lid therefor, mechanism mounted on the lid and depending into the reservoir for raising oil to a sight feed, a sight feed

mounted on the top of the lid, and a force pump mounted on top of the lid, to force the oil that falls from said feed into the machine to be lubricated.

2. In a force feed lubricator, an oil reservoir, a lid therefor, mechanism mounted on the lid and depending into the reservoir for raising oil to a sight feed, a sight feed mounted on the top of the lid, and a force pump mounted on the top of the lid, and 70 means for actuating the force pump mounted on the lid and depending therefrom, said pump having a vertically reciprocating rod 75 connected to the said means.

3. In a force feed lubricator, an oil reservoir, a lid therefor, mechanism mounted on the lid and depending into the reservoir for raising oil to a sight feed, a sight feed mounted on the top of the lid, and a force pump mounted on the top of the lid, and 80 means for actuating the force pump mounted on the lid and depending therefrom, said pump having a vertically reciprocating rod 85 connected to the said means, a cross shaft in said reservoir and separable connection from 90 said shaft to said actuating means.

4. In a force feed lubricator, an oil reservoir, a lid therefor, mechanism mounted on the lid and depending into the reservoir for raising oil to a sight feed, a sight feed 95 mounted on the top of the lid, and a force pump mounted on top of the lid, and means for actuating the force pump mounted on the lid and depending therefrom, a cross shaft in said reservoir and separable connection 100 from said shaft to said actuating means.

5. In a force feed lubricator, an oil reservoir, a lid therefor, a force pump mounted on top of said lid, means in the reservoir 105 for raising oil to said pump, said pump having a pump rod and means in the reservoir for actuating said rod.

6. In a force feed lubricator, an oil reservoir, a lid therefor, a sight feed mounted 110 on the lid, and a force pump mounted on said lid, said pump having a vertical chamber, and a vertically reciprocating rod, and valves arranged so that the rod forces oil out of the pump chamber upon its upward 115 stroke.

7. In a force feed lubricator, an oil reservoir, an oil trunk mounted outside of said reservoir, means for raising oil into said trunk, a sight feed at the end of said trunk, 120 and a force pump having a casing unitary with said trunk, and having a rod and valves arranged to force oil out upon an upward movement of the rod.

8. In a force feed lubricator, an oil reservoir, a lid therefor, a force pump mounted on top of said lid, means in the reservoir for raising oil to said pump, said pump having a pump rod, and means in the reservoir 125 for actuating said rod, and a pump 130

chamber for said pump, an outlet valve for said chamber, the same being located above said chamber.

9. In a force-feed lubricator, an oil reservoir, a lid therefor, an oil trunk mounted on said lid, means for raising oil into said trunk, a sight feed mounted at the end of the trunk, and a force pump having a casing unitary with the trunk, said pump having a rod for the pump and means for actuating the same.

10. In a force feed lubricator, an oil reservoir, a lid therefor, an oil trunk mounted on said lid, means for raising oil into said trunk, a sight feed mounted at the end of the trunk, and a force pump having a casing unitary with the trunk, said pump having a rod and means for actuating the said rod mounted on the lid and depending therefrom into the reservoir.

11. In a force feed lubricator, an oil reservoir, a lid therefor, a force pump mounted on the lid, same having a rod depending into the reservoir, an eccentric mechanism suspended from the lid into the reservoir for actuating the rod, a driving shaft in the reservoir and separable connection therefrom to the eccentric mechanism.

12. In a force feed lubricator, an oil reservoir, a lid therefor, a force pump mounted on the lid, same having a rod depending into the reservoir, an eccentric mechanism suspended from the lid into the reservoir for actuating the rod, a driving shaft in the reservoir and separable connection therefrom to the eccentric mechanism, a sight

feed into said pump and means connected to said eccentric mechanism for raising oil from the reservoir into the sight feed.

13. In a force feed lubricator, an oil reservoir, a lid therefor, a force pump mounted on the lid, same having a rod depending into the reservoir, an eccentric mechanism suspended from the lid into the reservoir for actuating the rod, a driving shaft in the reservoir, a gear on the shaft and a gear on the eccentric mechanism to mesh therewith.

14. In a force feed lubricator, an oil reservoir, a lid therefor, an eccentric mechanism suspended from the lid, a sight feed for said lubricator, a member suspended from the lid having a pump chamber therein, a passageway from the chamber to the sight feed, and a plunger for said pump chamber adjustably connected to the eccentric mechanism.

15. In a force feed lubricator, an oil reservoir, a lid therefor, an eccentric mechanism suspended from the lid, a sight feed for said lubricator, a member suspended from the lid having a pump chamber therein, passageways from the chamber to the sight feed, a plunger for said pump chamber, screwthreaded connection between the plunger and the eccentric mechanism, and means to prevent rotation of the plunger when adjusted in any desired position with regard to said eccentric mechanism.
